UNITED STATES PATENT OFFICE

ERNST BARTELS, OF BANDOENG, JAVA, DUTCH EAST INDIES

LEAF TURNER

Application filed May 14, 1930. Serial No. 452,368.

This invention relates to leaf turners for books, music and the like.

A primary object of the invention is to construct a leaf turner which will operate indefinitely without necessitating any resetting of the mechanism.

Another object is to so construct such a mechanism that by a simple pressure of a switch closing button the leaf of a book or sheet of music will be turned and the mechanism automatically reset ready for turning of the next leaf when the button is again actuated.

Another object is to so construct a music leaf turner that after a leaf has been turned it will be engaged and held by automatically operating means which when the next leaf is to be turned will be released and thrown out of the way to provide for the reception of the on-coming leaf and will then drop into engagement with said leaf and hold it until the next leaf is to be turned.

In carrying out these objects, the invention is susceptible of a wide range of modification without departing from the spirit or sacrificing any of the advantages of the claimed invention; there being shown in the drawings for illustrative purposes a preferred and practical form, in which:

Figure 1 represents a top plan view of a music leaf turner constructed in accordance with this invention with the leaf turning arm shown in inoperative position in full line and in operative actuating position in dotted line;

Fig. 2 is a longitudinal vertical section thereof with parts broken out and in elevation;

Fig. 3 is an enlarged detail longitudinal section showing the means for releasing the leaf engaging member;

Fig. 4 is a horizontal section taken on the line 4-4 of Fig. 3;

Fig. 5 is a transverse section taken on the line 5-5 of Fig. 2;

Fig. 6 is an enlarged detail section showing the mechanism which controls the leaf holding device;

Fig. 7 is a similar view showing the mecha-

nism in a different position with the leaf holder elevated to release the leaf;

Fig. 8 is a horizontal section taken on the line 8-8 of Fig. 2;

Fig. 9 is a vertical section taken on the line 9-9 of Fig. 8;

Fig. 10 is an enlarged detail sectional view showing the vacuum controlling valve and its operating mechanism;

Fig. 11 is a detail perspective view of the leaf holding device detached;

Fig. 12 is a longitudinal section taken on the line 12-12 of Fig. 11;

Figs. 13, 14 and 15 are detail perspective views of the cams and their cooperating parts which control the operation of the leaf holder;

Fig. 16 is a diagrammatic view of the electric circuit which controls the operation of the mechanism.

In the embodiment illustrated the invention is shown in connection with a music holding stand including a base 1 from which rises a supporting standard 2 having a motor containing casing 3 adjustably mounted thereon and held by set screw or thumb screw 4.

The motor 5 mounted in the casing 3 is designed to be actuated or brought into operation by means of a push button or switch located at a point remote and indicated at S in Fig. 16. It is of course understood that the motor 5 may be of any suitable or desired construction capable of performing the duties which will be required of it. The shaft 6 of this motor has a gear wheel 7 mounted thereon as shown clearly in Fig. 2 with which meshes a cooperating gear 8 carried by a shaft 9 mounted in a suitable bearing 10 of an enclosing casing 11. This shaft 9 has a worm 12 which meshes with a worm gear 13 carried by a shaft 14 which is journaled in a suitable bearing 15 here shown projecting laterally from one side wall of the casing 11. Fixed to the shaft 14 which carries the worm gear 13 is a mutilated disk or cam 16 for a purpose presently to be described.

A crank arm 17 is also fixed to the shaft 14 and to the free end thereof is pivotally connected a link 18 which extends up into a

80

75

85

90

95

100

tubular casing 19 shown having threaded engagement at its lower end with the casing 11, (see Fig. 2). This link 18 is pivoted at its upper end to the lower end of a tubular 5 piston rod 20. This rod 20 is longitudinally slotted at its lower end as shown at 21, it being understood that there are two of these slots, one at each side of the piston rod, and through which are designed to project laterally extending studs 22 carried by the lower end of a rack bar 23 which extends through the piston rod 20 and the piston 25 carried by said rod through an opening in the upper wall of the housing. This rack bar 23 has 10 teeth 24 on one edge near its upper end and also is provided with a laterally extending downturned finger 26 for a purpose presently 15 to be described.

The piston 25 operates in a cylinder 19a formed at the upper end of the casing 19 as shown clearly in Fig. 2 and this piston operates in the cylinder to provide a vacuum in the chamber 27 when the piston is moved downwardly and which will be presently 20 more fully described.

Mounted on the upper end of the cylinder 19a is a housing 28 through an opening in the upper wall of which the rack bar 23 is designed to reciprocate. Journalled in suitable bearings in the housing 28 at the right hand end thereof is a shaft 29 which has fixed thereto in longitudinally spaced relation two gears 30 and 31. Gear 31 meshes with the teeth of the rack bar 23 while gear 30 meshes with the teeth of a rack bar 32 which extends in a plane at right angles to the rack bar 23 and is mounted in suitable bearings in the housing 28, and is designed to reciprocate in said bearings.

40 An air conduit 33 extends longitudinally of the housing 28 here shown mounted on the bottom thereof and is equipped at the end thereof adjacent the housing 19 with a head 34 having a lateral threaded extension 35 designed to be detachably mounted in the upper end or head of the vacuum chamber 27, see Figs. 2 and 10. The air duct or canal 36 which extends longitudinally through the member 33 also extends through the head 34 thereof being offset at its junction with the head and the body of the member 33 and then extends through the extension 35 providing communication between the vacuum chamber 27 and the canal of the member 33.

45 Located in the head 34 and intersecting the air ducts therein is a vertically movable valve 37 which has a transverse air duct or canal 38 therein designed to register when the valve is in normal open position with the conduit in the member 33 and with the conduit in the extension 35 thereby bringing into communication these conduits with each other and with the interior of the vacuum chamber.

50 Arranged beneath this valve 37 is a coiled spring 39 which exerts its tension to normally

force the valve outward into operative position, said outward movement being limited by a stop 40 mounted in the upper end of the head 34 as shown clearly in Fig. 10 and which when engaged by the valve holds the latter in normal operative position to bring the duct thereof into register with the ducts in the member 33 and extension 35.

This valve 37 is located in the path of the finger 26 carried by the rack bar 23 so that when said rack bar is retracted in a manner hereinafter described it will operate to engage said valve and force it inward against the tension of the spring 39 thereby cutting off communication between the air ducts in the member 33 and extension 35 and connecting the duct 38 with the atmosphere as shown clearly in Fig. 10 and which is designed for a purpose hereinafter to be described.

The outer end of the rack bar 32 has an offset terminal 32a which is provided with rack teeth arranged on an edge in a plane at right angles to the teeth at the other end thereof.

An arm 50 is swingably mounted on the outer end of the housing 28 and has a lateral extension 51 at its inner end which extends into the housing 28 and on which extension 51 is fixedly mounted a block or gear 52 having teeth 53 extending around a portion of its periphery as shown clearly in Fig. 13. A spring pressed pin 54 is mounted in the untoothed portion of the gear 52 and projects beyond the lower face thereof as shown clearly in Fig. 7, it being designed to ride on the upper face of a cam 60 which is mounted on a block 55 carried by an upstanding portion 38a of the member 33.

The cam 60 has on its lower face at one side thereof a depending cam finger 61 and on its upper face is provided with two inclined recesses or teeth 62 and 63 which are arranged in the path of the pin 54 for a purpose presently to be described. A coil spring 56 is arranged outside the housing 28 and connects the lateral extension 51 of the arm 50 to the housing and exerts its tension to swing arm 50 into the position shown at the right of Fig. 1 in which position it is arranged in a plane at right angles to the housing 28 and when so arranged is designed to hold its gripping member 70 engaged with the leaf of the book in connection with which it is to be used.

Depending from the free end of the arm 50 is the leaf gripping member 70. This member 70 is composed of a rubber leaf engaging member 71 provided with a plurality of suction cups 72 in its outer face which communicate by conduits 73 with a conduit 74 extending longitudinally of an arm 75 which carries at its free end the plate or rubber block 71. This arm 75 which is swingably connected with the arm 50 by means of a shaft 76 is designed to normally depend from arm 50 in a plane at right angles thereto as shown

clearly in Fig. 2 in which position it is adapted to engage the leaf of the book in connection with which it is to be used.

The outer end of the arm 50 which carries

5 the depending leaf engaging member 70 is shown provided with an enlargement or head 57 to accommodate the operating mechanism for the leaf gripping member 70 as will be now described.

10 The shaft 76 to which is fixed the arm 75 of the leaf gripping member 70 extends transversely through the head 57 of arm 50 and has fixedly secured thereto a gear wheel 77 which meshes with the teeth of a rack bar 78 70

15 mounted to slide longitudinally in the head 57, the operation of which controls the swinging movement of the member 70 relative to arm 50.

A coil spring 79 is connected at one end 20 with the rack bar 78 and at its other with the wall of the chamber of the head 57 within which said bar is mounted and exerts its tension to retract or draw the bar 78 within the head. A leaf spring 80 is shown engaging and forcing the bar 78 upward to insure the meshing of the teeth thereof with the gear 77.

A cylinder 81 is formed in the inner portion of the head 57 and a piston 85 is mounted to reciprocate therein. A threaded closure 82 closes the outer end of the cylinder 81 and has a channel or small conduit 83 extending obliquely therethrough and communicating with the conduit 58 which ex- 30

35 tends longitudinally through the arm 50 and through the extension 51 of said arm. This conduit 58 communicates with a co-extensive conduit 55a in the member 55 and through said conduit 55a communicates with the conduit

40 36 so that a continuous air passage is formed from the vacuum chamber 27 through the member 33 and its connection with the arm 50 and through said arm 50 to the piston cylinder 81. The conduit 58 in the arm 50

45 also extends into a conduit 76a in the shaft 76 and through this conduit 76a communicates with the conduit 74 which leads to the vacuum cups 72 on the leaf gripping member 70. The release of vacuum in the ducts 58

50 and 76a is necessary for two purposes, first, to release member 70 from its grip on the paper and second, to guide piston 85 backward, that is to the left. See Figs. 3 and 4.

A piston rod 86 which carries at its front 55 end the piston 85 extends rearwardly through the outer end wall of the cylinder 81 into the chamber 59 in which the rack 78 is mounted and is designed to cooperate with said bar 78 in a manner presently to be described.

60 A coiled spring 87 is arranged between the rear face of the piston 85 and the end wall of the cylinder 81 as shown clearly in Figs. 3 and 4 and operates when expanded to project the piston 85 into the position shown in Fig. 2 which is the position the piston occupies

when vacuum is on in the chamber 27 and when the vacuum in said chamber 27 is released the vacuum at the rear of the piston 85 will operate to draw it in the position shown in Figs. 3 and 4 compressing the spring 87 70 when so doing.

A leaf holding member 90 is mounted in the outer end of the casing 28 and is designed to extend in a direction opposite to that occupied by the leaf gripping member 70 when the parts are in operation as shown in Fig. 1, the member 70 being in position to engage the leaf to be turned while the member 90 engages the leaf which has been turned and by means of which both of said leaves are held open for the inspection of the reader. This leaf holder 90 as shown is made in the form of a skeleton plate 91 rotatably mounted on a rod 92 and yieldably held by means of a coil spring 93, which is connected at one end with said rod and at the other end with the plate 91 as shown clearly in Figs. 11 and 12.

The rod 92 depends from the free end of an arm 94. Arm 94 is journalled in one side wall of the housing 28 and has secured to the end of said arm which is mounted within the housing a coiled spring 95 the free end of

85 which has radially extending finger 96 adapted to be engaged with one wall of the housing as is shown clearly in Figs. 6 and 7. This spring 95 is designed to return the arm 94 to initial position after it has been swung upwardly by engagement of the cam 61 with a laterally extending lug 97 on the arm 94 which occurs at predetermined intervals controlled by the swinging of the arm 50 which carries the leaf turning element 70. It is of course understood that it is necessary to swing the leaf holding member 90 up out of the path of the oncoming turned leaf which is carried by the member 70 and after said turned leaf has been properly positioned in relation to the other turned leaves the member 90 is lowered into operative engagement therewith by means of the coiled spring 95.

100 Mounted on an insulating plate 65 are two contact fingers 66 and 67, the finger 66 engaging the periphery of the mutilated cam 16 and the finger 67 has a downturned end 68 arranged above and in the path of the finger 66 so that when said finger 66 is raised by the circular portion of the cam 16 the contacts will be closed and the circuit completed. When the disk 16 has turned sufficiently to bring the mutilated portion thereof under the finger 66 said contact or finger will drop onto said portion and thereby move away from the contact 68 breaking the circuit and stopping the motor.

110 In the use of this apparatus the parts being in the position shown in Figs. 1 and 2 in full line with the contacts 66 and 67 open, when the button is depressed the current energizes the motor 5 causing it to turn to the right and through the gears 7, 8, shaft 9, worm 12, and 120

130 65 2 which is the position the piston occupies

gear 13 rotates the mutilated disk or cam 16 and through its connection with link 18 and piston 20 retracts or moves the piston 25 downward in the vacuum cylinder 27 producing a vacuum in advance of the piston which causes suction through the air conduits connected with the vacuum chamber of the cylinder as will be presently more fully described, and at the same time when the piston reaches a predetermined point the studs 22 on the rack bar 23 becoming engaged with the end of the slot 21 exerts a pull on the rack bar moving it inward and through its meshing engagement with the gear 31 causes gear 30 to operate the rack bar 32 toward the right. This movement of the rack bar 32 causes the gear 52 on the outer end of the rack bar 32 to be turned toward the right and thereby swing the arm 50 carrying the leaf engaging member 70 in the direction of the arrows shown in Fig. 1. It is to be understood that this operation is being performed while the mutilated or cam disk 16 is turning under the influence of the energizing of the motor 5 and when it reaches the flat portion therein or rather when the flat portion comes under the contact 66 this contact drops and separates from contact 67 breaking the circuit and cutting off the motor.

This operation of the piston, rack bars, and gears to swing the leaf engaging member 70 carried by the arm 50 in the direction of the arrows shown in Fig. 1 turns the leaf with which said member 70 is engaged, the suction or vacuum produced in chamber 27 by the downward movement of the piston 25 operates through the air conduit or channel which extends through the members 33, 55, 60 and 74 to the vacuum cups 72 carried by the member 70 and operates thereby to securely hold the page or leaf to be turned in contact with this member 70 so that when the arm 50 is turned outwardly the leaf engaged by the member 70 will be turned with it.

When the member 70 carrying the leaf to be turned has travelled to 90 degrees or into the dotted line position of the member 70 shown in Fig. 1 the finger 61 of the cam 60 will engage the finger 97 and lift the leaf gripping member 91 through an angle of about 90 degrees moving it out of engagement with the leaf at the left which it has been holding so as to clear the way for the oncoming leaf carried by the member 70. At the moment when this leaf gripping or holding member 91 is raised the leaf carried by the member 70 will be moved to the left against the leaves already there and immediately thereafter the member 91 will lower again incident to the passage of the cam 61 from under the finger 97 and the tension of the spring 95 and the new leaf will then become fixed at the left and held by the member 91.

At the instant the arm 50 carrying the leaf engaging member 70 has travelled through 160 degrees the finger 26 of the rack bar 23 will have been lowered into engagement with the valve 37 and press said valve inward against the tension of spring 39 cutting off communication between the vacuum chamber 27 and conduit leading to the cups on the member 70 breaking the vacuum of said cups and exhausting the air to the atmosphere which is accomplished by means of the L-shaped air canal in the valve 37, numbered 38 and shown in Fig. 10 of the drawings. When this occurs the vacuum in front of the piston 85 is also broken while that in the rear thereof remains intact. When this occurs the piston 85 moves outwardly or towards the left under the vacuum in the rear thereof and compresses the spring 87 as shown in Figs. 3 and 4. When this occurs the rack bar 78 is moved longitudinally outward and upward into the position shown in Fig. 3 and this movement of said rack bar operates through the gear 77 to swing the arm 75 carrying the leaf gripping member 70 upward to permit the leaf which it has been carrying to pass from under it without noise and into position to be held by the member 90.

It will thus be seen that after the arm 50 has travelled through an arc of 190 degrees and deposited the leaf to be turned at the left of the book it will under action of the spring 56 be swung back into initial position as shown at Fig. 1 in full lines ready for the next operation.

The rack bar 78 has a laterally extending stud 78a near its inner end resting on the rib 88 which is disposed at an incline as shown clearly in Fig. 3. This rib 88 is preferably arranged on an incline of about 30 degrees so that the stud 78a sliding along this rib will guide the bar 78 causing the bar 78 to be tilted as shown in Fig. 3 and at that moment the arm 75 carrying the leaf gripping member 70 reaches its extreme upward position and the piston rod 86 passes above the inner end of bar 78 as shown in Fig. 3 and permits the bar 78 to swing back to normal position under the tension of the spring 79 and move the piston 85 back to the position shown in Fig. 2 ready for the next operation.

The swinging back of the arm 50 into initial position causes the rack bar 32 to move toward the right thereby operating through the gears 30 and 31 to raise the bar 23 which carries with it the finger 26 thus releasing the valve 37 and permitting it under the action of the spring 39 to move outward into operative position as shown in Fig. 2 with the air conduit in the member 32 and extension 35 in register ready for the operation of the piston on the next pressing of the electric button.

It is of course understood that when the spring 79 pulls the rack bar 78 backward, the leaf spring 80 operates to push it upward and thus bring it into alignment with the

piston rod 86 ready for the next operation. The push button S shown in Figs. 2 and 16 controls the circuit to the motor 5 when the same is depressed through wires 121 and 122 which are enclosed in the sheath 120, shown in Fig. 2. The wires 121 and 122 are connected with a source of current as shown in Fig. 16 and such connection will be made usually with a house supply.

10 Wire 123 connects wire 121 with the contact member 66 while wire 124 connects the contact 67 with wire 122. Thus it will be seen that the motor 5 will be started by the push button S but will be maintained in a closed 15 circuit through the contacting members 66 and 68. When, however, the cam 16 has reached the position shown in Fig. 16, the current to the motor will be broken when the parts 66 and 68 are separated.

20 From the above description it will be seen that this leaf turner when once set may be operated repeatedly by a quick pressure and release on the push button which is located convenient to the operator so that all the 25 leaves of a book may be turned without any resetting of the mechanism.

It is of course to be understood that this 30 apparatus may be used in connection with music stands, book rests, or any other suitable support. It is also understood that the arm 50 may be made of varying lengths to adapt it for use in connection with books of different sizes.

35 When it is desired to turn the leaf of the book from left to right in a direction opposite to that shown in the drawings, and which of course will necessarily be done manually, the leaf turner is raised to disengage the leaf 40 engaging elements or the book may be lowered and when the leaves have been freed from the members 70 and 90 the leaf or leaves may be turned back and forth at the will of the operator, and after the proper 45 place has been found the leaf turner may be again placed in operative position as shown.

Without further description it is thought that the features and advantages of the invention will be readily apparent to those 50 skilled in the art, and it will, of course, be understood that changes in the form, proportion and minor details of construction may be resorted to, without departing from the spirit of the invention or its scope as claimed.

55 I claim:

1. In a leaf turner a supporting structure, an arm swingably mounted on said structure, a leaf engaging member swingably mounted on said arm, vacuum controlled 60 means connected to operate said member and the arm, automatic means for producing and releasing the vacuum whereby said member and arm may be swung simultaneously for positioning the leaf and for moving the leaf 65 engaging member away from the leaf and

for returning the arm and member to an operative position.

2. In a leaf turner a supporting structure, an arm swingably mounted on said structure, a leaf engaging member swingably mounted 70 on said arm, vacuum controlled means connected to operate said member and the arm, electric means under the control of an operator for producing and releasing the vacuum whereby said member and arm may be 75 swung in one direction on the forming of the vacuum, and means automatically operable on the release of the vacuum for moving the member away from the leaf and for resetting the leaf engaging member. 80

3. In a leaf turner a supporting structure, an arm swingably mounted on said structure, a leaf engaging member swingably mounted on said arm, vacuum controlled means connected to swing said member and arm in one direction, means operable by the swinging of said arm to release the vacuum, means for moving the member away from the leaf, and means for returning the arm and leaf engaging member to initial position on the release of the vacuum. 85

4. A leaf turner comprising a supporting structure, an arm swingably mounted on said structure, a leaf engaging member swingably mounted on said arm, suction means carried by said member to engage the leaf to be turned, means for producing suction in said leaf engaging means, means operable by said suction producing means, to swing said arm and leaf engaging member a predetermined 90 distance, and suction releasing means operable by the means which controls the swinging movement of the leaf engaging member to disengage said member from the leaf when it reaches a predetermined point and means for automatically returning the parts to initial position. 100

5. In a leaf turner a supporting structure, a leaf engaging and turning member swingably mounted on said structure, means for operating said turning member, means for engaging and holding the leaf after it has been turned by said turning member, means for releasing said holding means and moving it out of the path of an oncoming leaf and operable by the movement of the turning member, and means for returning said leaf holder to engage the turned leaf and hold it until the approach of the next leaf. 110

6. In a leaf turner a supporting structure, a leaf engaging member swingably mounted on said structure, means for actuating said swingable member, a leaf holder to engage and hold the leaf after it has been turned by said turning member, means for releasing said holding means and moving it out of the path of an oncoming leaf, said means being actuated by the swinging of the leaf turning means and means for returning said 125 leaf 130

- leaf holder to operative position to engage the turned leaf.
7. In a leaf turner a supporting structure, a leaf engaging member swingably mounted on said structure, means for actuating said swingable member, a leaf holder to engage and hold the leaf after it has been turned by said turning member, means for releasing said holding means and moving it out of the path of an oncoming leaf, said means being actuated by the swinging of the leaf turning means and means for returning said leaf holder to operative position to engage the turned leaf, and means operable to swing said leaf engaging member upward out of the path of the turned leaf and permit the leaf which it has been carrying to pass from under it in the position to be held by the holder.
8. In a leaf turner a supporting structure, a leaf engaging and turning member swingably mounted on said structure, means for holding the leaf after it has been turned, means for operating said leaf turning member and means operable by the leaf turning member to release the holding member and swing it out of the way of the approach of the turned leaf.
9. In a leaf turner a supporting structure, a leaf engaging and turning member swingably mounted on said structure, means for holding the leaf after it has been turned, means for operating said leaf turning member and means operable by the leaf turning member to release the holding member and swing it out of the way of the approach of the turned leaf, and means for returning said leaf holder to engage the turned leaf and hold it until the approach of the next leaf.
